Filed July 28, 1970, Ser. No. 24,174

Term of patent 14 years

Int. Cl. D8—01; D15—03

U.S. Cl. D40—1

FIG. 1 is a perspective view of a motor shroud for lawn mower showing my new design, the broken lines being for illustrative purposes only;

FIG. 2 is a top plan view of the motor shroud of FIG. 1;

FIG. 3 is a front elevational view of the motor shroud of FIG. 1;

FIG. 4 is a rear elevational view of the motor shroud of FIG. 1; and

FIG. 5 is a side elevational view of the motor shroud of FIG. 1.

The opposite side is a mirror image of the design shown in FIG. 5.

I claim:

The ornamental design for a motor shroud for lawn mower, as shown and described.
